US00D861968S

(12) **United States Design Patent** (10) Patent No.: **US D861,968 S**
Walker et al. (45) Date of Patent: ** Oct. 1, 2019

(54) **STROBE COMPONENT**

(71) Applicant: **Talon Aerolytics (Holding), Inc.**, West Point, GA (US)

(72) Inventors: **Jerry G. Walker**, Fayetteville, GA (US); **Ricky L. Walker**, Newnan, GA (US); **Austin Wingo**, Opelika, AL (US); **Eric Hare**, Opelika, AL (US); **Phillip Bevel**, Opelika, AL (US)

(73) Assignee: **Talon Aerolytics (Holding), Inc.**, West Point, GA (US)

(**) Term: **15 Years**

(21) Appl. No.: **29/621,339**

(22) Filed: **Oct. 6, 2017**

(51) LOC (12) Cl. **26-99**

(52) U.S. Cl.

USPC **D26/113**

(57) **CLAIM**

The ornamental design for a strobe component, as shown and described.

DESCRIPTION

FIG. 1 is a first perspective view of a strobe component showing our new design;

FIG. 2 is a second perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is a third perspective view thereof;

FIG. 10 is a fourth perspective view thereof;

FIG. 11 is another front elevation view thereof;

FIG. 12 is another rear elevation view thereof;

FIG. 13 is another right elevation view thereof;

FIG. 14 is another left elevation view thereof;

FIG. 15 is another top plan view thereof; and,

FIG. 16 is another bottom plan view thereof.

The broken line shown in the drawings are for the purpose of illustrating environment and form no part of the claimed design.

1 Claim, 14 Drawing Sheets
